VALVE TAG

Application filed August 2, 1930. Serial No. 472,542.

This invention relates to valve tags and more particularly to an indicating tag adapted to be disposed in an underground valve box of the type generally known as a 5 "Buffalo" box for purposes of precluding the insertion of a suitable T-wrench into the valve box for engagement with the valve stem of a valve controlling a main conduit requiring first reading of the indicia on the valve tag thereby compelling a prospective operator of such a valve to first note and check up the number of such valve.

In public utility household services such for example as in the distribution of gas for 15 heating and lighting purposes, water or the like, various main conduits are tapped off of a central main running from a central dispensing station and each of the main conduits are further tapped for distribution to individual consumers in localized communities. 20 Occasionally, particularly in the case of gas distribution, due to unavoidable corrosion of conduits, the individual consumer conduits require repair. The general practice is to 25 caution such individual consumers who obtain gas from the particular main conduit sought to be repaired to the effect that between certain hours gas will not be available for consumption. It frequently happens that 30 a plurality of main control valves are located in close proximity to each other. In such cases, an operator is sent out to close the particular valve controlling the main conduit sought to be repaired at the predetermined 35 hour and when the repairs have been completed, the same or another operator is dispatched to open such valve. In cases where a plurality of such valve boxes are located in close proximity to each other, there is always 40 a danger of an operator cutting off the wrong main line or conduit and in such a case, those consumers who have not been previously warned and who may be at the time using gas from such line, are subjected to danger 45 of explosion or asphyxiation when the valve is again turned on to rectify the error.

The present invention is designed to eliminate such dangers as are connected with present practice. To this end it is proposed to 50 interpose in each valve or "Buffalo" box a

suitable pivoted tag supported in the valve box adjacent the cover thereof to normally extend across the path of movement of the usual tool employed to operate the valve. The tag is preferably disposed in a horizontal 55 plane transverse to the axis of the valve box so that upon removal of the usual valve box cover, it is first necessary to move the tag out of the usual path of movement of such a valve operating tool. To provide for suitable 60 checking up by a prospective operator of the valve as to the correctness of the identity of the valve desired to be operated, the tag is provided with indicia for suitable identification of the valve. Thus when a prospective 65 operator first removes the cover of the valve box, he is immediately confronted with the valve tag which precludes insertion of the usual tool required for the operation of the valve and at the same time he is also confronted 70 with the number of other identifying characters of the valve. He may thus quickly and readily check up on the identity of the valve.

Preferably, the valve tag is mounted for 75 pivotal movement from a horizontal plane upwardly into the space normally occupied by the valve box cover. Thus after the valve has been properly identified, the operator must swing the valve tag to an upright position out of the path of movement of the usual 80 valve operating tool, in order to be able to insert the tool into the valve box and proceed with the operation of the valve and removal of the tool. Before he can replace the valve box cover however, he must first replace the 85 valve tag. Thus it is compulsory upon the operator to first elevate the tag prior to operation of the valve, and it is equally compulsory upon him to replace the valve tag in its normal operative horizontal position, 90 prior to leaving the valve box, in order to be able to replace the box cover.

More specifically, one modified form of the valve tag comprises a sheet metal stamping 95 preferably formed of one-piece which is provided with a pair of spaced ears adapted to embrace the head of a suitable stud secured to the wall of the valve box adjacent the cover seat. To provide for a suitable brace or supporting portion to maintain the tag in hori- 100

zontal or transverse position with respect to the path of accessibility of the valve, the portion of the tag between the ears is bent downwardly and then reversely so that in the operative position of the valve tag, the reversely bent portion will abut the inner periphery of the valve box adjacent the stud.

In another modified form of a device embodying the salient features of the present invention, the tag comprises a malleable iron casting, the main body portion being preferably circular in configuration and being provided with suitable reinforcing ribs on its under side. A pair of these ribs extend in proximate parallel relation and terminate in integral parallel ears beyond the outer periphery, such ribs being formed on a taper whereby the ears are relatively wide. The outer edges of the ears are slightly beveled to engage the inner periphery of a valve box thereby functioning as stop means. The main body portion is further provided with a somewhat thicker reinforcing peripheral rim. A pair of aligned reinforcing ribs provided on the under side of the body portion extend radially outwardly to the rim periphery, their inner ends joining the parallel ribs hereinbefore noted.

The ears are provided with aligned transverse recesses for the passage therethrough of a suitable pivot pin which is journaled in the head of a suitable stud disposed between the ears. Preferably, a sheet metal plate etched or stamped with suitable identifying indicia is seated upon the upper side of the body portion within the rim, the plate being secured to the tag body by means of rivets or in any other suitable or desired manner.

In cases where new valve or "Buffalo" boxes are to be installed the valve tag may be suitably secured to the valve box wall by merely drilling a hole to accommodate the stud and a nut threaded over the end of the stud thereby permanently securing the tag in place inasmuch as the nut will, in the ground embedded position of the valve box, be on the outside of the box. In cases of valve boxes already installed, a suitable hole may be drilled from the inner periphery of the valve box through the outer adjacent the lower portion of the cover seat, the hole then suitably tapped and the stud threaded into such tapped hole.

The advantages of the device embodying the features of the present invention are:

A permanently attached valve tag is provided; the valve tag being disposed immediately under the usual box cover, is maintained free from the effects of inclement weather conditions; the device may be quickly and readily installed in present valve boxes already in use; it is durable and may be economically manufactured and installed; it is positioned where it must be encountered before the valve which is to be operated may

be so operated and must be replaced after operation of the valve; and in its inoperative position in no way interferes with the normal operation of the valve.

Other and further objects and advantages will appear from the following detailed description of a preferred embodiment of my invention illustrated in the accompanying drawings, in which:

Figure 1 is a vertical section through a valve or "Buffalo" box illustrating the usual position of the valve and main, and embodying one form of the present invention;

Figure 2 is a plan view looking down into the box with the valve tag in operative or obstructing position, the cover of the valve box having been removed;

Figure 3 is an enlarged fragmentary section of the upper end of the valve box taken substantially along the line 3-3 of Figure 2;

Figure 4 is a side elevation of the valve tag and stud per se;

Figure 5 is a section similar to that shown in Figure 4, illustrating a modified mounting of the tag;

Figure 6 is a view similar to Figure 2, illustrating a modified form of valve tag;

Figure 7 is a side elevation of the tag and stud per se shown in Figure 6;

Figure 8 is a section taken along the line 8-8 of Figure 6, the valve box and nut being omitted; and

Figure 9 is a section taken along the line 9-9 of Figure 8.

In Figure 1, I have illustrated in section 10 a commonly employed form of valve box generally indicated at 10 comprising an upper section 11 and a lower section 12, the latter being provided with external threads at its upper end and the former being provided with internal threads to take onto the threads of the section 12 for purposes of adjusting the valve box to the required length. The lower section 12 is provided with an enlarged portion 13 at its extreme lower end which is adapted to be positioned over a valve 14 associated in a main conduit 15.

The upper section 11 is provided at its upper end with an enlarged portion 16 forming with the body portion of section 11, a seat 17 for suitably accommodating a box cover 18.

Referring now more particularly to Figures 2, 3 and 4, the valve tag of the present form comprises a one-piece sheet metal body portion 19 of substantially circular configuration provided at one side thereof with two laterally extending spaced lugs or extensions 20, each of which terminates in a rolled ear 21. The extensions or lugs 20 are preferably formed by stamping and the portion therebetween is bent downwardly as indicated at 22 in angular relation to the body portion 19 and then is bent upwardly to form a suitable stop portion 23. The ears 21 are suit-

ably spaced apart to accommodate therebetween a bolt or screw head 24 of square cross section, this head 24 being provided with a transverse hole 25. A suitable headed pin 26 extends through the ears 21 and hole 25 and is peened or riveted over for retention against displacement. The body portion of the stud is threaded as indicated at 27.

Referring more particularly to Figure 3, the valve box is provided with a hole 28 to accommodate the body portion of the stud adjacent and in proximity to the cover seat 17. The stud is then passed through this hole 28 and a suitable nut 29 threaded over 15 the body portion to rigidly secure the stud to the wall of the valve box.

I prefer to employ Monel metal in the construction of the valve tag body portion 19 but it will be understood that any other 20 sheet metal may be employed.

The body portion 19 of the valve tag is provided with suitably stamped indicia 30 for identification of the valve 14.

As will be readily apparent from Figures 25 1 and 3, the normal position of the valve tag body portion 19 is horizontal with the brace or stop portion 23 abutting against the inner periphery of the wall of the valve box in proximity to the stud so that the valve tag body portion 19 extends transversely across the normal path of movement of a suitable T-wrench when it is desired to connect the usual socket of such wrench with the valve stem. Thus immediately upon removal of 35 cover 18, an operator must first take note of the valve tag due to the requirement that it be moved out of the path of the tool or wrench, and in doing so he is promptly confronted with the indicia identifying the particular valve encased by the valve box. Thus 40 prior to the operation of the valve, an operator is compelled to take note of the characteristic designation 30 of the valve. In the inoperative or non-obstructing position, the tag body portion 19 assumes the position 45 illustrated in dotted lines in Figure 3. When the valve has been suitably operated, in order to replace the cover 18, it is necessary for the operator to first replace the valve tag to its 50 normal operative position as indicated in full lines in Figures 1 and 3. Thus the operator 55 is positively compelled to replace the valve tag. It will be readily apparent that by the interposition of the valve tag embodying the salient features of the present invention, the element of human error or negligence is entirely eliminated.

In Figure 5, I have illustrated a modified mounting of the valve tag. The valve tag body portion 19' with its integral extensions 60 20', stop portion 23' and suitable indica are identical in structure with that disclosed in the modification illustrated in Figures 1 to 4 inclusive. The modification primarily resides in the provision of a suitably threaded

stud 31 preferably employing the U. S. standard thread. In the instant case, the tag is applied to the upper end of a valve box which is already embedded in the ground and in this case a suitable hole 32 is drilled from the top 70 of the valve box at a slight angle downwardly adjacent the valve box cover seat 17', the hole 32 being suitably tapped to accommodate the threads of the stud 31. The function and operation of the valve tag illustrated in Figure 5 will be clearly apparent.

Referring now more particularly to Figures 6 to 9 inclusive, I have illustrated a modified form of valve tag preferably formed of malleable cast iron. In this case, the tag comprises a main body portion 40, the central portion 41 of which is relatively thin. The body portion 40 is preferably of circular configuration and is provided at its outer 80 periphery with a reinforcing rim 42. The under side of the body portion 40 is suitably reinforced by a pair of parallel depending tapered ribs 43 which terminate to one side of the body portion 40 and beyond the rim 42 thereof in spaced parallel ears 44. Each of these ears 44 is defined by an upper edge extending from the upper side of the rim 42, then curved upwardly away from the rim periphery, and terminated at its outer 85 edge in a beveled edge 45 perpendicular to the plane of the body portion 40. The purpose of the bevel edges 45 will be hereinafter explained. The ears 44 are suitably spaced apart to accommodate therebetween the head 90 46 of a stud 47, the ears being provided with suitable aligned holes 48 and the head having a transverse hole 49 therein, holes 48 and 49 being adapted to be aligned for the reception 95 therethrough of a headed pin 50, the opposite end of which may be suitably riveted or peened over as indicated at 51 to suitably connect the tag with the stud 47 for relative pivotal movement. As in the case of the 100 mounting stud illustrated in Figures 1 to 5 inclusive, the stud 47 in the instant modification is threaded as indicated at 52 either for the purpose of receiving thereon a nut 53 or for purposes of direct threading into a suitably tapped hole in the valve box upper section 105 adjacent the cover seat. 110

A second pair of aligned ribs are provided on the under side of the body portion 40 and extend radially outwardly to the rim 42 from the parallel ribs 43.

Inasmuch as the rim 42 is substantially thicker than the central body portion 41, a suitable seat 55 is provided for the accommodation therein of a sheet metal identifying plate 56 upon which suitable indicia identifying the valve with which the tag is adapted to be associated may be etched or stamped. I prefer to employ sheet aluminum for the identifying plate although it will be readily understood that any other suitable sheet 120 125 130

metal may be employed for the purpose. The plate 56 may be suitably retained in position in the seat 55 by rivets 57 although any other suitable or preferred means may be employed.

As will be apparent from Figure 6, the bevel edges 45 of the ears 44 will serve as stop portions to retain the tag in horizontal position and will be readily accommodated to the inner periphery of the valve box.

The function and operation of the modified form of tag illustrated in Figures 6 to 9 inclusive will be readily apparent.

It will be of course understood that in place of casting, the tag may be made in any other preferable or desired manner and any other preferred metal may be employed.

While I have illustrated several preferred embodiments of my invention, I do not wish to be limited thereto as certain changes may be made therein without departing from the essence of the invention or the spirit and scope of the appended claims.

What I claim and desire to secure by Letters Patent is:

1. The combination with a valve box including a valve at one end thereof accessible from the other end, of means interposed between said latter end and said valve in the path of accessibility whereby accessibility of said valve is normally precluded, and indicia on said means suitably identifying said valve to a prospective operator of the valve.

2. The combination with a valve box including a valve at one end thereof accessible from the other end and a cover seat and cover at said latter end, of a stud secured to said box, a plate pivotally supported thereon for movement into and out of the path of accessibility of said valve, and stop means on said plate adjacent the pivotal support adapted to engage the inner periphery of said box to normally retain said plate across said path of accessibility thereby normally precluding access to said valve.

3. The combination with a valve box including a valve at one end thereof accessible from the other end and a cover seat and cover at said latter end, of a stud secured to said box, a plate pivotally supported thereon for movement into and out of the path of accessibility of said valve, stop means on said plate adjacent the pivotal support adapted to engage the inner periphery of said box to normally retain said plate across said path of accessibility thereby normally precluding access to said valve, and indicia on said plate suitably identifying said valve to a prospective operator.

4. The combination with a valve box including a valve at one end thereof accessible from the other end and a cover seat and cover at said latter end, of a stud secured to said box adjacent said cover seat and ex-

tending inwardly of the inner periphery of said box, a one-piece plate having a pair of spaced ears extending laterally therefrom, a pin passing through said ears and stud for pivotally supporting said plate on said stud, and an integral stop projection extending downwardly between said ears adapted to engage the inner periphery of said box to normally retain said plate in the path of accessibility of said valve thereby normally precluding access to the valve.

5. The combination with a valve box including a valve at one end thereof accessible from the other end and a cover seat and cover at said latter end, of a stud secured to said box adjacent said cover seat and extending inwardly of the inner periphery of said box, a plate member having a pair of spaced ears extending laterally therefrom, a pin passing through said ears and stud for pivotally supporting said plate member on said stud, an integral stop projection extending downwardly between said ears adapted to engage the inner periphery of said box to normally retain said plate in the path of accessibility of said valve thereby normally precluding access to the valve, and indicia on said valve suitably identifying said valve to a prospective operator.

6. The combination with a valve box including a valve accessible from one end of and through the box, a cover seat, and a cover adapted to be positioned in said seat, of means disposed in said box adjacent said cover seat and normally extending into the path of accessibility of said valve thereby normally precluding access to the valve through said end, said means being movable into the space normally occupied by said cover in inoperative position thereby requiring movement thereof to operative or accessibility precluding position prior to seating of said cover in its seat.

7. The combination with a valve box including a valve accessible from one end of and through the box, a cover seat, and a cover adapted to be positioned in said seat, of a plate pivotally associated with the inner periphery of said box adjacent said seat, and means bracing said plate for retaining the plate in a position normally precluding passage to said valve of an operating tool, said plate being swingable to an inoperative or non-precluding position to obstruct seating of said cover thereby requiring movement thereof to operative or precluding position prior to seating of said cover in its seat.

8. The combination with a valve box including a valve accessible from one end of and through the box, a cover seat, and a cover adapted to be positioned in said seat, of a stud connected to said box adjacent said seat, a plate pivotally connected to said stud for swinging movement into and out of a position for obstructing passage of a valve oper-

ating tool through said end to the valve, and stop means on said plate adapted to engage the inner periphery of said box adjacent said stud to limit movement of said plate in one direction to operative or obstructing position, said plate being movable to inoperative or non-obstructing position to preclude seating of said cover in its seat thereby requiring movement thereof to operative or tool obstructing position prior to seating of said cover.

9. The combination with a valve box including a valve accessible from one end of and through the box, a cover seat, and a cover adapted to be positioned in said seat, of a stud connected to said box adjacent said seat, a one-piece metal plate having spaced ears to accommodate said stud therebetween, a pin passing through said ears and stud for supporting said plate for pivotal movement in said box into and out of a position for obstructing passage of a valve operating tool through said end to said valve, and stop means on said plate adapted to engage the inner periphery of said box adjacent said stud to limit movement of said plate in one direction to operative or obstructing position, said plate being movable to inoperative or nonobstructing position to preclude seating of said cover in its seat thereby requiring movement thereof to operative or tool obstructing position prior to seating of said cover.

10. The combination with a valve box including a valve at one end thereof accessible from the other end, of a pivoted plate supported in said box and comprising a body portion, reinforcing ribs on said body, and a pair of spaced ears extending laterally from said body, said ears having stop portions thereon adapted to engage the inner periphery of said box to normally retain said plate across the path of accessibility thereby normally precluding access to said valve.

45 11. The combination with a valve box including a valve at one end thereof accessible from the other end, of a pivoted plate supported in said box and comprising a body portion, reinforcing ribs on said body, a pair of spaced ears extending laterally from said body, said ears having stop portions thereon adapted to engage the inner periphery of said box to normally retain said plate across the path of accessibility thereby normally precluding access to said valve, and an indicia bearing plate on said body portion.

In witness whereof, I hereunto subscribe my name this 31 day of July, 1930.

MATHEW G. MARKLE.
